UNITED STATES PATENT OFFICE.

FRANK B. WUEBBEN, OF DAYTON, OHIO.

AIR-TORPEDO.

1,273,303.

Specification of Letters Patent. Patented July 23, 1918.

Application filed July 11, 1917. Serial No. 179,897.

To all whom it may concern:

Be it known that I, FRANK B. WUEBBEN, a citizen of the United States, residing at Dayton, in the county of Montgomery and 5 State of Ohio, have invented new and useful Improvements in Air-Torpedoes, of which the following is a specification.

This invention relates to improvements in aerial torpedoes.

10 The primary object of the invention is to provide an aerial torpedo having an automatic exploding device adapted to cut off the power of the torpedo previously to the explosion to allow it to fall to the point of 15 most effective action.

Another object is to provide an improved construction for the body and supporting surfaces.

A further object is to provide means for 20 automatically maintaining the torpedo on a direct course.

A fourth object is to provide means which will hold the controlling surfaces to direct the torpedo upward, and which will be released after a predetermined interval to permit the torpedo to travel horizontally.

With these and other objects in view, I have incorporated my invention in the construction, combination, and arrangement of 30 parts hereinafter described, illustrated in the drawings, and having the novel features set forth in the claims.

In the drawings:

Figure 1 is a side elevation of the torpedo.

35 Fig. 2 is a fragmentary top plan view showing the covering material of one wing partly removed to expose the construction.

Fig. 3 is a longitudinal vertical section through the body of the torpedo.

40 Fig. 4 illustrates diagrammatically the controlling mechanism for cutting off the power and operating the elevator rudder.

Fig. 5 is a detailed view of the partition plate for the body.

45 The body 1 of the torpedo is of the customary elongated stream-line form to minimize air resistance, and is divided transversely intermediately of the ends into two sections, a forward section 2 for containing the explosive charge, and a rear section 3 inclosing the power plant and associated mechanism. Each section is preferably a

50 one-piece aluminum casting having walls of

considerable thickness, whereby in the explosion a large quantity of fragments is obtained without prohibitive weight; and the adjacent ends of the sections 2 and 3 are formed respectively with external and internal screw threads 4, 5 adapted for mutual engagement to securely lock the sections together.

The power plant consists in the present instance of a gasoline motor 6 mounted interiorly of the rear section 3, and driving, preferably by gears 7 and 8, the propeller 65 shaft 9, suitably journaled in bearings 10 attached to the body 1, and prolonged rearwardly through an opening 11 provided in the rear end of the body; and terminally provided with means shown as a flange 12 70 for driving attachment of the propeller 13. The motor 6 is provided with the usual fuel tank 14 and battery 15, or other ignition means, and for controlling the motor 6 the throttle 16 is preferably connected to a rod 75 17 prolonged through an opening in the body 1 for exterior attachment of a handle 18, rotatable to close and open the throttle; while one of the battery conductors 19 is brought through an opening 20 for insertion in the circuit of a switch 21 mounted on the outside of the body and adapted to be manually opened to stop the motor 6.

To retain the explosive charge 22 in the forward section a partition plate 23 is suitably secured, over the end of the section 2; and for firing the charge 22 after a predetermined interval to allow the torpedo to reach a desired point, I prefer to utilize a timing device 24 such as is commonly employed for explosive shells, screwthreaded or otherwise secured in an elongated hollow shank 24' similarly engaged in an opening 25 communicating with the charge chamber.

The shank 24' is, in the preferred form 95 shown, filled with slow-burning material constituting a time fuse.

To obtain the maximum effect, the torpedo is preferably adapted to fall to a desired distance from the ground before the explosion. 100 In the present instance, this is accomplished by inserting in the conductor 19 a spring opened switch 26 normally maintained closed by a combustible tension element shown as a cord 27 extending through an 105 opening 27' in the timer-shank 24' to con-

- tact with the combustible matter therein and terminally connected to an auxiliary lever 28 normally rotatable on the throttle-rod 17 and adapted to be secured to the rod 17 by 5 a thumb-screw 29. A spring 30 is provided for closing the throttle, 16, which in operation is opened a desired distance by the lever 18, and secured in the open position by tightening the screw 29 on the lever 28.
- 10 The supporting surfaces 31 preferably comprise frames 32 of wood or other suitable material having attached thereto a plurality of tension elements shown as rods 33 or wires extending inwardly and linked at 15 the inner ends to suitable connecting means shown as plates 34. The surfaces are covered with fabric in the usual manner, and are suitably attached to the body, as by bolting to flanges formed integrally with 20 and projecting laterally from the body and extending longitudinally thereof.

The usual vertical and horizontal rudders 37 and 38 are mounted in the present instance on the extremity of a bars 39 securely bolted or otherwise attached to and extending rearwardly from the body 1. To automatically maintain the torpedo on a direct course, the rudder 37 may be pivotally mounted on the bars 39 for lateral 30 swinging movement, and connected by suitable means shown as rods 40 to controlling flaps 41 swingingly attached toward the ends of the supporting surfaces 31. It will be seen that when a side-gust tending to deflect the torpedo from the proper course strikes either flap 41, the rudder 37 will be actuated to compensate for the disturbance by serving as a rudder.

Hinged to the rear edge of the horizontal 40 rudder 38 is a flap 42 constituting an elevator rudder for directing the movements of the torpedo in a vertical plane. In the preferred form shown, the flap 42 is adapted to be normally maintained against a stop 45 43 in a position to cause the torpedo to ascend. For this purpose a spring 44 is attached at one end to the flap 42 and provided at the other end with an eye 44' engaged by a catch 45 suitably pivoted as to 50 the frame of the stabilizing surface. The catch 45 is adapted to be disengaged from the eye 44' by a tension spring 46, normally restrained from action by a cord 47 attached at one end to the catch 45 and toward the 55 other extended through an opening 48 in the shank 24' of the timer 24 similarly to the cord 27, and terminally secured to any convenient portion of the structure.

In operation, the timer 24 is set before 60 releasing the torpedo to allow the latter to climb to a desired height before releasing the cord 27 to permit the controlling surfaces to move to the position for horizontal travel. The distance between the openings

48 and 27' is such as to permit the torpedo 65 to travel a desired distance horizontally before releasing the cord 27 to cut off the power, and the remaining portion of the time fuse is of such length that the torpedo will fall to a desired distance of the ground 70 before the explosion.

It is to be understood that the herein described embodiment of my invention is only one of many and varied forms comprehended within the spirit of the invention; 75 and the right is reserved to such variation, alteration, and modification as falls within the scope of the claims.

I claim:

1. A device of the class described comprising a body adapted to contain an explosive charge, propelling means for said body, an elevating plane for said body, a time fuse, and means operated by said time fuse for actuating said plane and for stopping the propelling means. 80

2. A device of the class described comprising a body adapted to contain an explosive charge, propelling means for said body, sustaining means for said body, steering means for said body, controlling flaps hinged to said sustaining means, connecting means for connecting said flaps to the steering means, a device for exploding the charge, and means actuated by said device 90 for rendering the propelling means inoperative. 95

3. In a device of the class described, a body adapted for containing an explosive charge, propelling means for said body, sustaining means for said body and controlling means for said body; a device for exploding such charge and having connection with said body, and means having connection with said propelling means whereby the propelling means will be rendered inoperative after a predetermined period of operation; the last mentioned means adapted to be actuated by said exploding device. 100

4. In a device of the class described, a body adapted for containing an explosive charge, propelling means for said body, sustaining means for said body, controlling surfaces for said body, and a device on the body for exploding such charge; means normally holding said controlling surfaces in a position for one direction of travel, the last mentioned means having connection with said exploding device whereby the said last mentioned means will be released after a predetermined interval to permit said controlling means to change the direction of travel. 110

5. In a device of the class described, a body adapted for containing an explosive charge, propelling means for said body, controlling surfaces for said body, sustaining means for said body, and a device on said 115 120 125

body for exploding such charge; means having connection with said controlling surfaces and said exploding device whereby the controlling surfaces will normally be retained in one position and will be permitted movement to another position after a predetermined interval of time, means having connection with said exploding device and said

propelling means whereby the propelling means will be rendered inoperative after a predetermined interval of time, and a mechanism for automatically governing said controlling surfaces.

In testimony whereof I affix my signature.

FRANK B. WUEBBEN.
